ABSTRACT: A combustion chamber for a gas turbine engine has a primary air inlet and a number of additional air nozzles at intervals along the chamber. Each of the air inlets has one or more holes in the inlet wall, so that air may be injected into the inlets or extracted therefrom. Air injection effectively reduces the inlet areas and extraction increases the inlet areas. The airflow through each inlet, or group of inlets, may thus be controlled, the arrangement being such that, irrespective of the proportion of the total airflow which enters each inlet, the resistance to airflow through the combustion chamber does not vary. The holes in the inlet walls may be tangential to create a vortex within the inlet.

COMBUSTION CHAMBERS FOR GAS TURBINE ENGINES

This invention relates to combustion chambers for gas turbine engines and has as an object to provide a combustion chamber in a convenient form.

A combustion chamber in accordance with the invention has a primary air inlet duct, secondary air inlet nozzles and dilution air inlet nozzles, each air entry point incorporating a fluidic airflow control device arranged so that the proportions of the total airflow through the respective air entry points can be varied without variation of the total resistance of the combustion chamber to airflow therethrough.

In the accompanying drawings

FIG. 1 is a fragmentary section through an annular combustion chamber incorporating an example of the invention,

FIG. 2 is a fragmentary enlargement of the part ringed in FIG. 1 and FIGS. 3 and 4 show, somewhat diagrammatically, two views of a part of an alternative embodiment.

The combustion chamber has an inner wall 10 and an outer wall 11 shaped to join at a circular leading end in which primary air inlet ducts 12 are formed. Each primary air inlet duct has a swirler 13 which incorporates control jet holes 14 through which high-pressure air can be injected. These holes 14 are arranged around the outer periphery of the swirler 13 so that when compressed air is injected the effective area of the swirler is reduced fluidically to reduce the airflow through the primary air inlet ducts. Conversely, when air is bled off through the holes 14 the effective area of the swirler is increased fluidically to increase the airflow through the primary inlet duct.

The walls 10, 11 of the combustion chamber adjacent the inlet end thereof are formed with secondary air inlet nozzles 15 constituted by inwardly directed flanges on the walls. In association with the nozzles 15 is an annular dished member 16 defining an annular air chamber 17. Drillings are formed in the flanges which open into the nozzles 15 on the upstream sides thereof. Thus when high-pressure air is applied to the chambers 17 jets will issue into the nozzles 15 and fluidically restrict flow of air into the combustion chamber. If on the other hand air is drawn from the chambers 17 the effective area of the nozzles 15 will be increased so that there will be increased airflow through the nozzles 15.

Downstream of the nozzles 15 the walls 10, 11 have dilution air inlet nozzles 18 similar to the nozzles 15. These nozzles 18 similarly have associated therewith fluidic flow control devices constituted by drillings in the nozzle flanges opening into chambers 19 to which air is supplied to decrease the effective areas of nozzles 18 and from which air is drawn to increase the effective area.

It will be noted that the provision of the fluidic control drillings on the upstream side only of the nozzles has the effect of changing the direction of the airflow through the nozzles as well as reducing the effective cross-sectional area of the nozzles.

At engine running conditions associated with the weaker overall air/fuel ratios for the combustion chamber, e.g., aircraft standoff flight conditions, the fluidic devices mentioned above are actuated to decrease flow through the primary and secondary air nozzles to a minimum value, whilst air is drawn from the chambers 19 to increase the airflow through nozzles

18 to a maximum value. At engine running conditions associated with the richer overall air/fuel ratios for the combustion chamber, e.g., aircraft takeoff conditions, the supply of compressed air to the holes 14 is stopped and air is drawn

5 from chambers 17 so that the primary and secondary airflows are increased. The chambers 19 are pressurized to reduce the dilution airflow. This changes the pattern of airflow in the combustion chamber to increase the quantity of air available to the burners which would be situated in the centers of the 10 respective swirlers 13. The change in direction of the secondary airflow causes increased reverse flow of secondary air to increase the rate of intermixing of fuel and air.

It is to be noted that the upper half of FIG. 1 shows airflow conditions obtaining at low throughput and the lower half shows conditions at high throughput.

The fluidic devices used in nozzles 15 and 18 may alternatively take the form of vortex amplifiers as shown in FIGS. 3 and 4 in which there are control drillings which can direct tangential jets of air into the nozzles to create swirl which will effectively reduce the area of the nozzles.

In either case the areas of the nozzles, the sizes of the control drillings and the control pressures used would be chosen so that there is no change in the overall resistance of the combustion chamber to airflow when changeover from one flow 20 condition to the other takes place.

Having thus described my invention what I claim as new and desire to secure by Letters Patent is:

1. A combustion chamber which includes a primary air inlet duct, secondary air inlet nozzles and dilution air inlet nozzles, 30 each air entry point incorporating a fluidic airflow control device arranged so that the proportions of the total airflow through the respective air entry points can be varied without variation of the total resistance of the combustion chamber to airflow therethrough.

2. A combustion chamber as claimed in claim 1 in which the primary air inlet duct incorporates holes through which air may be injected or withdrawn so as respectively to increase or decrease the effective area of the duct.

3. A combustion chamber as claimed in claim 2 in which the 40 said holes are formed in the outer periphery of the duct.

4. A combustion chamber as claimed in claim 1 in which the secondary air inlet nozzles are constituted by inwardly directed flanges on the walls of the chamber, said flanges being formed with drillings in the upstream sides thereof 45 through which air may be injected or withdrawn so as respectively to reduce or increase the effective areas of the nozzles.

5. A combustion chamber as claimed in claim 1 in which the dilution air inlet nozzles are constituted by inwardly directed flanges on the walls of the chamber, said flanges being formed with drillings through which, in use, high-pressure air is injected tangentially into the nozzles.

6. A combustion chamber as claimed in claim 1 in which the dilution air inlet nozzles are constituted by inwardly directed flanges on the walls of the chamber, said flanges being formed 55 with drillings in the upstream sides thereof through which air may be injected or withdrawn so as respectively to reduce or increase the effective areas of the nozzles.

7. A combustion chamber as claimed in claim 1 in which the secondary air inlet nozzles are constituted by inwardly directed flanges on the walls of the chamber, said flanges being formed with drillings through which in use high pressure air is injected tangentially through the nozzles.
